UNITED STATES PATENT OFFICE.

CHARLES F. KLEIN, OF CINCINNATI, OHIO, AND HUGO A. HECKER, OF BELLEVUE, KENTUCKY, ASSIGNEES TO THE F. M. WATKINS COMPANY, OF CINCINNATI, OHIO, A CORPORATION OF OHIO.

MANGLE.

SPECIFICATION forming part of Letters Patent No. 739,322, dated September 22, 1903.

Application filed May 23, 1901. Serial No. 61,649. (No model.)

To all whom it may concern:

Be it known that we, CHARLES F. KLEIN, of the city of Cincinnati, county of Hamilton, and State of Ohio, and HUGO A. HECKER, of the city of Bellevue, county of Campbell, and State of Kentucky, citizens of the United States, have invented certain new and useful Improvements in Mangles, of which the following is a full, clear, and exact description, reference being had to the accompanying drawings, forming part of this specification.

Our invention relates to mangles or ironing-machines for ironing for what in a steam-laundry is technically known as "flat work"—such as sheets, table-cloths, towels, napkins, &c.—and it has for its object to provide a machine simple and easy of operation, with large capacity, and for the finishing of both sides of the goods to be operated upon. This is accomplished by the peculiar arrangement of steam-heated chests and padded rolls and the rotating steam-heated cylinder and apron, whereby the goods to be operated upon are first passed between the chests and pad-rolls, being carried from one to the other over a curved plate, thereby ironing the lower side of same, and thence passing between the steam-heated cylinder and an endless apron, whereby the upper side is ironed and delivered to a receiving-table.

The curved plate above mentioned is preferably perforated, as the heat radiated from the sides of the chest will thereby be allowed to pass upward through the perforations and assist in drying the goods as they pass over it.

An additional feature of our mangle is that small pieces too short to be carried over the above plate may be placed by the operator at the delivery side of the machine on the top of the steam-heated cylinder and be ironed only by the action of the cylinder and apron, such pieces usually not requiring more ironing than they would thus obtain.

We also provide a machine in which the covering of the rolls and apron, which are the parts most frequently requiring renewal, shall be as inexpensive as possible and in which the pressure upon these parts shall be under simple and easy control of the operator.

To these ends our invention is particularly

adapted, as will be seen in the following description.

In the drawings, Figure 1 is a side elevation of our improved machine, the side being the one in which the belt for communicating motion to the machine is connected. Fig. 2 is a vertical longitudinal section of the same. Fig. 3 is a side elevation of the opposite side of the machine from that shown in Fig. 1. Fig. 4 is an enlarged top view, and Fig. 5 an enlarged side view, of the mechanism for controlling the pressure upon the padded rolls. Fig. 6 is an enlarged front view, and Fig. 7 a plan view, of the mechanism for controlling the movement of the apron. Figs. 8 and 9 are respectively a side and sectional view of the doffer-plate on the delivery end of the mangle. Fig. 10 is a plan view of the apron-controlling mechanism, showing both ends. Fig. 11 is a perspective view of the gearing for controlling the pressure of the padded rolls.

In the drawings, A and A' are the main frames of the machines, which are tied together by the cross-girths B and B'.

C and C' are padded rolls constructed of wrought-iron tubing and covered with felt and canvas, operating in boxes D and D', which are mounted in suitable recesses in the main frames.

E and E' (see Fig. 2) are steam-heated chests having polished concave ironing-surfaces to fit the periphery of the padded rolls.

F, Fig. 2, is a curved plate with a polished surface and preferably perforated with a large number of small holes.

It would be practicable in a machine of less capacity to omit steam-chest E without departing from the spirit of our invention, and for machines of greater capacity it may be desirable to use two pair of chests, each with its adjusting device, as shown at Figs. 4 and 5.

G is a box for the reception of the goods to be operated upon, and G' is a feed-plate upon which the goods are laid and straightened to enter into the machine.

H is a smooth-surfaced steam-heated rotating cylinder or drum of large diameter with relation to the padded rolls and having the lower part of its circumference encircled by an endless apron J of flexible material, such

as canvas, mounted upon rollers K, K', K², and K³ and having a roller K⁴ pressing upon its front side to deflect the apron, giving room for inserting the edge of the table L as far under the roll K³ as possible.

5 M is a doffer-plate of sheet metal attached to circular collars M', (see Fig. 9,) which are pivotally mounted upon the inner ends of the journal-boxes M².

10 N N' are journal-boxes for the roll K', mounted upon screws N' N', operating in bearings N² N² and connected through worm-gears N³ N⁴ and the shafts N⁵ to the hand-wheel N⁶, through the medium of which the

15 roll is traversed backward or forward, the object being to take up the slack in the apron, or vice versa, leaving the apron in a slack condition when the machine is not in operation. In practical experience it is found

20 that aprons of this class have a tendency to shift sidewise from one end of the roller. To obviate this, the journal-bearings O and O² for the bar or roller K² are pivotally mounted upon swivel sector-arms O' and O³ by

25 means of studs O⁹, formed on or extending laterally from the sides of the bearings O and O², said swivel sector-arms being pivoted or hung at O⁸ on supports O⁸, projecting from the girth B. Sector-teeth O⁴ are cut upon

30 the inner ends of the swivel-arms O' O³, which are engaged by worms O⁵ of the same hand—that is, both right-handed or both left-handed worms—mounted on the shaft O⁶, to which a hand-wheel O⁷ is attached. If the

35 apron J has a tendency to run toward one side of the machine, the hand-wheel O⁷ is rotated, so that through the medium of the worms on the shaft O⁶ the swivel-arm on that side is thrown out, while the corresponding

40 swivel at the other end is thrown in, thus shifting the apron back into proper position.

Referring to Figs. 4 and 5, will be seen the mechanism by which the pressure of the padded rolls upon the heated chests is controlled.

45 D D' are the journal-boxes within which the rolls are mounted at each end, operating vertically in suitable recesses in the frames A A'. The boxes each have a projection D² D³, formed upon their upper surface, to which is

50 connected an eyebolt D⁵, passing through the levers D⁶ D⁷, with lock-nuts D⁸ upon their upper ends. The levers are pivotally connected at one end to suitable lugs D⁹ D¹⁰ on the frames, the other end being pivotally connected to a square or rectangular block D¹¹

D¹², having a hole through its center, through which passes the upper and threaded end of a rod D¹³ D¹⁴, and having a lock-nut D¹⁵ D¹⁶ upon each side of the block. A portion 24 of

55 this rod is formed in a square shape where it passes through the frame at D¹⁷ to prevent its turning. The lower end of this rod is also threaded and passes through the worm-wheels D¹⁸ D¹⁹, which are threaded to suit. These

60 wheels D¹⁸ D¹⁹ are in mesh with the worm-wheels D²⁰, mounted upon a shaft D²¹, with a hand-wheel D²² for revolving the same. It is

evident that turning this hand-wheel will cause all the rods D¹³ D¹⁴ to be elevated or depressed simultaneously, according to the direction in which it is rotated, care being taken to have one of each pair threaded with a right-hand thread and the other of each pair having a left-hand thread. The levers D⁶ D⁷ are formed with a cup-shaped recess in their 75 central part, in which is placed a spring D²³, bearing upon the journal-boxes D D', by which the pressure is made yielding, allowing goods of different thicknesses to pass between the rolls and chests without constantly altering 80 the position of the levers.

Referring to Figs. 3, 8, and 9, M³ represents levers mounted pivotally at each side of the frame at M⁴ and having in their upper ends journal-boxes M², in which is mounted the 85 roll K³. These journal-boxes are fitted in square slots in these levers M³ to prevent their turning. One end of each box is turned on its inside to a cylindrical shape and has fitted thereon a circular collar M', which may 90 be rotated thereon and secured at any desired point by the set-screws M⁵. To these collars is fitted a curved plate M, called a "doffer-plate," whose object is to strip the goods as they reach this point from the rotating cylinder H and cause them to pass over the roll K³ and down upon the table L, where they are received by an operator and taken away. A doffer-plate such as this is not an 95 entirely new thing; but we believe the method of mounting same on the journal-boxes in a pivotal manner is new, whereby the plate may be adjusted so as to just touch the rotating cylinder.

It will be understood, of course, that the 105 rolls C C' and the cylinder H are driven at the proper rate of speed by suitable power, and we have shown in the drawings the trains of gearing and the band-wheel by means of which the ironing-rolls and ironing-cylinder 110 are rotated. We have not, however, lettered or described this driving-gearing, as the construction and operation will be evident from an inspection of the drawings.

The operation of the machine will be evident from the foregoing description. The articles to be ironed are fed under the padded roll C, over the perforated plate F, and under the padded roll C', by which operation they are thoroughly ironed on one side by 120 contact with the steam-chests E E' under pressure of the padded rolls, the heat from the steam-chests rising through the perforated plate taking up the bulk of the water in the articles. The goods then continue on between the endless apron and the steam-heated cylinder H and by contact therewith are ironed on the other side and dried, whence they are delivered by the doffer-plate to the 125 delivery-table L.

Having thus described our invention, what we claim, and desire to secure by Letters Patent, is—

1. In a mangle, a plurality of padded rolls,

- heating-chests against which said rolls turn for smoothing one side of the goods, said rolls being separated by a drying-space, a curved, perforated plate bridging said space, 5 in combination with a smooth-surfaced drum of larger diameter than the padded rolls, means for heating said drum, means for revolving the padded rolls and drum in the same direction, and means for receiving the goods 10 from the padded rolls and directing them to the drum, whereby the goods are smoothed on both sides and dried in their passage through the machine beneath said rolls and drum.
- 15 2. In a mangle, the combination with a supporting-frame, a pair of padded rolls and heating-chests against which said rolls run, journal-boxes for said rolls movably mounted in said supporting-frame, levers pivoted to 20 the frame on opposite sides of said rolls, springs between said levers and journal-
- boxes, rods attached to the free adjacent ends of said levers, threaded nuts on said rods, and a worm-shaft arranged to simultaneously engage and operate said nuts to move said rods and regulate the pressure of said springs. 25
3. In a mangle, the combination, with a rotating cylinder and an endless apron in contact therewith, a series of rollers over which said apron travels, journal-bearings for one 30 of said rolls having cylindrical portions with rotatable collars mounted thereon, set-screws for holding same, and a semicylindrical doffer-plate mounted on said collars, whereby said doffer-plate may be adjusted for readily 35 stripping the ironed article from the cylinder, substantially as shown and described.
